UNITED STATES PATENT OFFICE.

RICHARD F. WEBER, OF SACRAMENTO, CALIFORNIA.

ERASING-SHIELD.

1,237,979.

Specification of Letters Patent. Patented Aug. 21, 1917.

Application filed October 25, 1916. Serial No. 127,678.

To all whom it may concern:

Be it known that I, RICHARD F. WEBER, a citizen of the United States, residing at Sacramento, in the county of Sacramento and State of California, have invented new and useful Improvements in Erasing-Shields, of which the following is a specification.

This invention comprehends the provision of a new article of manufacture adapted for use in connection with a typewriter when erasures are being made, to protect the paper against undue injury, and to also receive the material resulting from the erasure on the surface of the paper, thereby preventing this material from collecting upon the different parts of the mechanism of the machine which is objectionable for various reasons.

In carrying out the invention I construct a device for the above mentioned purposes, from a single blank of material, thus rendering it cheap to manufacture and sell, the device further embodying a holder for an eraser whereby the two articles may be associated for the convenience of the user.

The nature and advantages of the invention will be better understood when the following detail description is read in connection with the accompanying drawing, the invention residing in the construction, combination and arrangement of parts as claimed.

In the drawing forming part of this specification like numerals of reference indicate similar parts in the several views and wherein:—

Figure 1 is a perspective view of the device constructed in accordance with my invention.

Fig. 2 is a sectional view therethrough also showing the manner of using the same.

Fig. 3 is a plan view of the blank from which the device is formed.

From a surface examination of the drawing it will be noted that the device forming the subject matter of the invention is constructed from a single blank of material indicated generally at A, which initially is perfectly flat. In constructing the article, the body portion thereof indicated at 10 is curved in the manner clearly illustrated in Fig. 2, while the lower edge of the material terminates to provide a trough 11. Projecting from the opposite longitudinal edges 55 of the body portion 10 are extensions 12, which subsequent to the formation of the

trough 11 are adapted to be bent forwardly to provide end walls for the trough which close the opposite ends of the latter. The extensions 12 may be secured to the adjacent ends of the trough in any suitable manner, but the end walls 12 are preferably provided with suitable apertures 13 which receive the bendable tongues 14 projecting laterally from the front wall of the trough, the tongues 14 subsequent to being passed through the apertures 13 being bent in the manner illustrated in Fig. 1. Depending from the lower edge of one of the end walls 12 is a resilient finger 15 which is curved upwardly as at 16 in juxtaposition to said end wall, defining with the latter a resilient clamp holder for the eraser 17. By reason of this construction it will be manifest that the article and the eraser 17 can be associated which makes it very convenient for the typist, as these elements are always used together, it of course being understood that the eraser can be easily removed from the holder when its use is desired and replaced within the holder without any trouble or difficulty.

The body portion 10 is curved to form to the curvature of the platen or cylinder 18 of the typewriter, against which it is adapted to bear while in use. In practice the curved body portion is arranged in the manner illustrated in Fig. 2 with the slot 19 of the body portion 10 arranged over the particular word or words, or other matter to be erased from the paper. The slot 19 permits the insertion of an eraser therethrough for the purpose just mentioned, and by reason of the particular arrangement of the trough 11 with respect to the slot 19 it is obvious that the trough will receive the material resulting from the erasure on the surface of the paper, thus preventing this material from collecting upon the mechanism of the machine.

While it is believed that from the foregoing description the nature and advantages of the invention will be readily apparent I desire to have it understood that what is herein shown and described is merely illustrative of the preferred embodiment of the invention, and that such changes may be resorted to when desired as fall within the scope of what is claimed.

What is claimed is:—

A device of the class described constructed from a single blank of material and includ-

ing a curved body portion having a slot for the insertion of an eraser therethrough, said body portion terminating to provide a trough arranged below said slot, laterally disposed extensions projecting from the opposite longitudinal edges of said body and adapted to be bent at right angles thereto

defining walls closing the opposite ends of said trough, and a resilient finger projecting from one of said extensions and adapted to 10 be bent upwardly in juxtaposition thereto.

In testimony whereof I affix my signature.

RICHARD F. WEBER.
